UNITED STATES PATENT OFFICE

158,145

RULER

George J. Staab, Springfield, N. J.

Application April 22, 1948, Serial No. 145,910

Term of patent 14 years

(Cl. D52—1)

To all whom it may concern:

Be it known that I, George J. Staab, a citizen of the United States of America and a resident of Springfield, in the county of Union and State of New Jersey, have invented a new, original, and ornamental Design for a Ruler, of which the following is a specification, reference being had to the accompanying drawing, forming a part thereof.

Figure 1 is a top plan view of a ruler, showing my new design;

Figure 2 is a bottom plan view of the ruler;

Figure 3 is an enlarged fragmentary plan view of the portion of the ruler bounded by the lines 3—3 of Figure 1;

Figure 4 is a transverse vertical sectional view, approximately on the plane of the line 4—4 of Figure 3;

Figure 5 is a similar view, approximately on the plane of the line 5—5 of Figure 3;

Figure 6 is a fragmentary vertical longitudinal sectional view, approximately on the plane of the line 6—6 of Figure 3, and

Figure 7 is a fragmentary sectional perspective view of the ruler.

I claim:

The ornamental design for a ruler, as shown.

GEORGE J. STAAB.
